CABINET FOR AN INPUT-OUTPUT DEVICE FOR A DATA HANDLING SYSTEM

Gregory Fossella, Marshfield, Mass., and John R. Bittner
and Kenneth C. McCartney, Waynesboro, Va., as-
signors to General Electric Company, Waynesboro, Va.

Filed Jan. 2, 1974, Ser. No. 430,024

Term of patent 14 years

Int. Cl. D14—02

U.S. Cl. D26—5 C

FIG.1.

FIG.2.

FIG.3.

FIG.4.

FIG.5.

FIG. 1 is a perspective view of a cabinet for an input-output device for a data handling system, showing our new design;

FIG. 2 is a top plan view;

FIGS. 3 and 4 are side elevation views; and

FIG. 5 is a rear elevation view.

We claim:

The ornamental design for a cabinet for an input-output device for a data handling system, substantially as shown and described.
